UNITED STATES PATENT OFFICE.

FERDINAND C. GAMMONS AND CLARENCE M. SHAW, OF BRIDGEWATER, MASSACHUSETTS, ASSIGNORS TO THE EAGLE COTTON GIN COMPANY, OF SAME PLACE.

COTTON-GIN BLAST-FLUE.

SPECIFICATION forming part of Letters Patent No. 536,200, dated March 26, 1895.

Application filed January 11, 1895. Serial No. 534,557. (No model.)

To all whom it may concern:

Be it known that we, FERDINAND C. GAMMONS and CLARENCE M. SHAW, citizens of the United States, residing at Bridgewater, in the county of Plymouth and State of Massachusetts, have invented certain Improvements in Cotton-Gin Blast-Flues for Conveying Lint-Cotton from the Gin to the Condenser or other Receptacle, of which the following is a full, clear, and exact description, reference being had to the accompanying drawings, making part of this specification, in which—

Figure 1 is a plan of a battery of cotton-gins provided with blast-flues constructed in accordance with our invention. Fig. 2 is an enlarged perspective view of the "hood" or end of the blast-flue, which is connected with the outlet opening at the back of the cotton-gin. Fig. 3 is a longitudinal horizontal section through the "hood" shown in Fig. 2. Fig. 4 is a transverse vertical section on the line 4, 4, of Fig. 3.

Our invention relates to the construction of cotton-gin blast-flues for conveying lint-cotton from the gin to the condenser or other location, and has for its object to reduce to a minimum the friction of the air and cotton in the blast-flue at the "hood" or point where said blast-flue is connected with the gin, and also to avoid clogging or obstruction of the flue by the concentration of cotton at this point. Hitherto it has been customary to connect the gin with the blast-flue by means of a ninety-degree elbow having a flaring mouth or "hood" fitting the discharge-opening at the back of the gin. This construction however is objectionable on account of the friction of the air and cotton as they impinge against the inclined sides of the flaring hood by which they are directed into the elbow or common center where another sudden change of direction occurs, and as the cotton from all parts of the discharge-opening at the back of the gin is concentrated at the said elbow, it frequently accumulates at this point, thus clogging the flue and stopping its operation.

Our invention is designed to obviate these difficulties and consists in a blast-flue connecting-hood having an inlet opening corresponding in size to that of the discharge-

opening at the back of the gin to which the "hood" is fitted, and having a straight semi-tubular back and two substantially parallel end-walls extending forward at an angle from the ends of its inlet opening, the said semi-tubular back and the forward end wall merging into an outlet separate from and independent of the hoods and flues of the other gins and adapted thereby to have an individual flue leading from said outlet to the point of delivery, as hereinafter more fully set forth and specifically claimed.

In the said drawings A, A, A, A, represent a battery of cotton gins, each of which is provided with a separate and independent blast-flue B, for conducting the lint-cotton to the condenser C, or other desired location.

D represents the "hood" which forms the connection between the discharge-opening at the back of the gin A, and the main portion 7c of the blast-flue B. This "hood" D, which is preferably composed of sheet metal, is provided with an elongated rectangular inlet opening b, corresponding in size and shape to the discharge-opening at the back of the gin to which the "hood" is fitted, as shown in Fig. 1, the top and bottom edges of the side-walls c, c, and the flanges d, e, forming suitable means of attachment to flanges around the edge of said discharge-opening of 80 the gin.

f represents the back of the "hood" which is located directly opposite the discharge-opening at the back of the gin, and is of semi-tubular form or curved transversely, 85 as shown in Figs. 2, 3, and 4, in which form it presents a smooth rounded surface without angles, and offers the least possible resistance or obstruction to the free passage of the lint-cotton to the tubular outlet g, of the "hood," 90 at which point it is connected with the main portion of the flue B.

The end-wall h, of the "hood" opposite to its outlet g, is inclined forward toward the same at an acute angle, whereby it is caused 95 to deflect the air and with it the cotton with the minimum of resistance to the straight back f, and thence to the outlet g; said back f being preferably inclined to the plane of the inlet opening b, from the end-wall h, to 100

the outlet *g*, whereby the sectional area of the "hood" is gradually increased in size as it approaches said outlet *g*, thus avoiding liability of clogging or obstruction by affording greater space near the outlet end of the hood to accommodate the cotton coming from all parts of the discharge-opening at the back of the gin.

5 The end-wall *k*, of the "hood" nearest to the outlet *g*, is also inclined forward at an angle to the inlet-opening *b*, and is substantially parallel with the opposite end-wall *h*, and consequently offers no obstruction or resistance to the air and cotton as it passes from this end of the discharge-opening at the back of the gin to the outlet *g*.

10 The end-wall *h*, is preferably provided with a glass covered opening *m*, to permit of a view of the interior of the "hood," said opening, when the glass is removed, serving as a hand-hole to afford access to the interior of the "hood."

15 By the employment of our improved "hood," elbows of ninety degrees hitherto used to bring the blast-flues into a position parallel with the gins in the direction of their length are entirely dispensed with, and all of the cotton as it leaves the gin starts in a natural course or direction toward the point of delivery and continues the same uninterruptedly with the least possible amount of friction, the elbows used being bent at a very slight angle, as shown in Fig. 1. Hence with our construction the blast or conveyer-flue is 20 practically shortened to a minimum, and the cotton caused to pass in the most direct line possible from the gin to the point of delivery, thus distributing the friction over the entire length of the flue instead of concentrating it at one point, thereby avoiding clogging and obstruction, whereas with the flaring-mouthed "hood" heretofore in use, a portion of the cotton on leaving the gin was forced by the inward incline on one side of the "hood" to start 25 in a direction exactly opposite to that finally taken, thus causing it to travel a longer distance, and also be retarded by excessive friction and sudden changes of direction before reaching the main portion of the blast-flue, all 30 of which difficulties are avoided in a "hood" constructed in accordance with our invention.

What we claim as our invention, and desire to secure by Letters Patent, is—

35 1. In a cotton-gin blast-flue, a connecting-hood, having an inlet-opening corresponding in size to that of the discharge-opening at the

back of the gin to which the hood is fitted, and having a straight semi-tubular back, and two substantially parallel end-walls extending forward at an angle from the ends of its inlet 60 opening, the said semi-tubular back and the forward end wall merging into an outlet separate from and independent of the hoods and flues of the other gins and adapted thereby to have an individual flue from said outlet 65 to the point of delivery, substantially as set forth.

2. In a cotton-gin blast-flue, a connecting-hood, having an inlet opening corresponding in size to that of the discharge-opening at the 70 back of the gin to which the hood is fitted, and having a straight semi-tubular back *f*, and two substantially parallel end-walls *h*, *k*, extending forward at an angle from the ends of its inlet-opening, the sectional area of said 75 hood increasing in size as it approaches the outlet or point where it is connected with the main portion of the blast-flue, the said outlet being formed at the juncture of the semi-tubular back with the forward end wall and 80 wholly independent of and separate from the hoods and flues of other gins to provide for an individual flue from said outlet to the point of delivery, substantially as set forth.

3. In a cotton-gin blast-flue, a connecting 85 hood *D*, having an inlet-opening *b* in front, corresponding in size to that of the discharge-opening at the back of the gin to which the hood is fitted, and having a tubular outlet *g*, a straight back *f* of semi-circular form in 90 cross section and inclined at an angle to the plane of the inlet-opening *b*, and two substantially parallel end-walls *h*, *k*, extending forward at an angle from the ends of the inlet-opening *b*, the end wall *k* and the tubular back 95 merging into the tubular outlet *g* and said outlet being separate from and independent of the hoods and flues of other gins to provide for an individual flue therefrom to the point of delivery the sectional area of said 100 hood gradually increasing in size from the end-wall *h*, to the outlet or point where it is connected with the main portion of the blast-flue, all constructed to operate substantially 105 in the manner and for the purpose described.

Witness our hands this 7th day of January, 1895.

A. D. 1895.

FERDINAND C. GAMMONS.
CLARENCE M. SHAW.
